Application August 13, 1940, Serial No. 352,451

4 Claims. (Cl. 28—40)

This invention relates to an automatic leasing machine to be used in connection with warp handling apparatus, such as ball warpers, singers and the like, whereby leases can be made in the warp without stopping the same.

It is a well known fact among those versed in textiles that it is necessary to form sheds in a warp at predetermined points and pass there-through a thread to separate the ends in two or more sections. Although the distance between the lease points varies, it has been found that 500 yards is a convenient length of warp between these points. Since the average warp beam contains 10,000 yards or more of material, it is evident that quite a number of leases must be taken; hence the necessity of having a machine for quickly and effectively doing this work.

It is an object of this invention to provide a machine for taking a lease in a moving warp which is capable of automatically releasing all portions of the lease thread simultaneously, so that a straight lease will be provided. Specifically the releasing means comprises a lease string clamp located at each edge of the warp and a retractible comb therebetween. The comb penetrates the warp and prevents the lease string from moving until the warp moves a predetermined distance, at which time the ends of the lease strings are automatically unclamped and the comb is simultaneously retracted to permit the string to move along with the warp.

It is another object of this invention to provide a leasing machine capable of inserting a lease string in a warp of minimum length. Usually the lease string extends across the warp two times and has its ends tied together. Heretofore, the points in the warp at which the lease thread was inserted were widely separated, thereby resulting in a portion of the lease thread projecting beyond the selvages of the warp. These projecting ends are objectionable because they frequently hang in machines subsequently used in the processing of the yarn, such as mercerizing machines and the like. In the present invention, the points at which the lease thread is inserted through the warp are close to each other, resulting in less overhang beyond the selvages.

Some of the objects of the invention having been stated, other objects will appear as the description proceeds, when taken in connection with the accompanying drawings, in which—

Figure 1 is a view of my device shown in association with a ball warping machine;

Figure 2 is an elevation, taken along the line 2—2 in Figure 1, with certain portions thereof

broken away and other portions shown in section, showing the interior mechanism of the lease forming apparatus;

Figure 3 is a vertical sectional view taken along the line 3—3 in Figure 1;

Figure 4 is a plan view, showing the reed in section, taken along the line 4—4 in Figure 1;

Figure 5 is a transverse vertical sectional view taken along the line 5—5 in Figure 4;

Figure 6 is an isometric view of a portion of the shed forming reed shown in the right hand portion of Figures 4 and 5;

Figure 7 is an isometric sectional view taken along the line 7—7 in Figures 2 and 4;

Figure 8 is an isometric sectional view taken along the line 8—8 in Figures 2 and 4;

Figure 9 is a vertical sectional view taken along the line 9—9 in Figure 3;

Figure 10 is an isometric view of the lease thread hook bar with the central portion thereof broken away;

Figure 11 is an isometric schematic view showing one position of the parts of the lease forming apparatus during the taking of a lease;

Figure 12 is an isometric view similar to Figure 11, but showing the position of the lease forming apparatus at another time during the forming of the lease;

Figure 13 is a schematic wiring diagram of the invention;

Figure 14 is a plan view of the lease forming apparatus showing a slightly modified form of means for inserting the ends of the lease thread through the moving warp sheds;

Figure 15 is an elevation looking at the near side of Figure 14;

Figure 16 is an elevation looking at the far side of Figure 14;

Figure 17 is a transverse vertical sectional view taken along the lines 17—17 in Figure 15;

Figure 18 is an isometric detailed view showing the position of one of the lease thread inserting prongs as it appears when it has penetrated the shed and is between the clamping means on one end of the apparatus.

Referring more specifically to the drawings, the numeral 10 denotes a conventional creel having a plurality of packages of yarn 11 mounted thereon. Each of the packages has an end 12 emanating therefrom which passes through a comb 14 on a warper 15. After passing through the warper, the ends again pass through another comb 16, and at this time, the ends are in a sheet form commonly termed a warp, and which is broadly designated by the refer-

ence character W. As heretofore stated, it is desirable to form a lease at predetermined intervals in this warp and therefore for the convenience of description and illustration the warp is divided into two layers, namely, W1 and W2. As a general rule, the warp ends W1 and W2, alternate, that is every other warp is W1 and each of the remaining warp ends is W2, although it is to be understood that any arrangement of the warp ends can be made without departing from the spirit of the present invention. In other words, the warp ends W1, when forming a shed, are divided into one layer and the warp ends W2 are divided into another layer and it is between these two layers that the lease string is inserted.

By observing Figures 5 and 6, it is seen that each warp end W1 passes through an elongated slot or dent 17 in reed 18; whereas, the warp ends W2 pass through a very much shorter slot or dent 19 in this same reed. When the layers W1 and W2 travel in a common plane forming a single warp W, the comb 18 is disposed in a vertical position as shown in Figure 1; therefore, the warp ends W1 and W2 will travel in the central portions of their respective slots or dents in the reed 18.

The reed 18 is fixedly secured upon the free end of levers 21, said levers having the other ends thereof fixedly secured to a rod 22, and this rod is mounted in brackets 23 on lease forming apparatus 24. Fixedly secured to one end of the rod or shaft 22 is a lever 26, said lever having its free end mounted in a slot 27 of plate 28 (Figure 2). This slot has notches or indentations 29 and 30 therein, into which the projecting portion 26a of lever 26 is adapted to fit. When the comb is in bold line position as shown in Figure 1, the projection 26a of the lever will fit into the notch or cavity 29 (see Figure 2). On the other hand when the comb 18 is in the uppermost dotted line position 18a, the projection 26a of the handle 26 will engage the notched portion 30. Whereas, if it is desired to lower the comb 18 to the dotted line position 18b in Figure 1, the lever 26 and the projection 26a is allowed to rotate to the uppermost portion of slot 27.

When the comb 18 is rotated upwardly to dotted line position 18a (Figure 1) the warp ends W2 will be engaged by the lower portions of the short slots 19 in the reed 18 (see Figures 5 and 6) and therefore, these warp ends will be raised to uppermost dotted line position, thus forming a shed. Due to the fact that the slots or dents 17 are very much longer than the slots or dents 19, in the reed 18, the warp ends W1 will not be disturbed but continue to travel in a horizontal plane. Likewise when the comb 18 is lowered to dotted line position 18b, as shown in Figure 1, the ends W2 will be contacted by the upper portion of the short dents or slots 19 and therefore be moved to lowermost dotted line position shown in Figure 1, thus forming a second shed. In the last shed, the warp ends W1 will still travel in a substantially horizontal plane.

The reed 18 is rotated to the positions 18a and 18b when it is desired to form sheds through which the ends of a lease string 32 are inserted. It is necessary to insert the lease thread between the warp sheds W1 and W2 when the reed is in the position 18a and to also insert this same thread through the warp sheds when the reed is in the position 18b. In other words, the lease thread resembles a pair of loosely

woven successive filling ends in a piece of cloth.

The comb 18 is adapted to vertically manipulate the warp ends W2 relative to the uppermost portion of the lease forming apparatus 24. 5 After the shed has been formed and the lease string placed therein, the string is held in position until a predetermined length of warp has passed by the leasing machine at which time the lease thread is automatically released from the apparatus 24 and allowed to pass along with the warp W over header roll 35 and then downwardly onto cheeses 36 of winding machine 37.

The leasing apparatus comprises a pair of hollow upright supporting members 40 and 41, the upper ends of which have mounted thereon a plate 42. Plate 42 has a plurality of vertically disposed slots in the opposed edges thereof in which vertically disposed splits or wires 43 and 44 are adapted to have vertical movement. The splits 43 are alined in one row to form one comb, whereas the splits 44 are alined in another row to form a second comb which is parallel to the first comb and disposed only a short distance away. Figures 2, 3 and 9 illustrate the structure of the lease forming apparatus and it is here seen that the lower ends of the splits 43 and 44 are secured to an inverted U-shaped bar 45, said bar being mounted on the upper end of a vertically slidable shaft 46. Shaft 46 has its lower end slidably mounted in a hollow shaft 47, which, in turn, is supported by side pieces 48. These side pieces serve as supports and braces and are attached to the spaced upright members 40 and 41.

35 The lower end of the shaft 46 has a tension spring 50 secured thereto, the lower end of said spring being secured to a cap member 51 which closes the lower end of the hollow shaft 47. The spring serves to pull the splits 43 and 44 downwardly at all times to the position shown in Figure 2, at which time the upper ends thereof are flush top, or slightly below, the top edge of the plate 42. In order to confine the splits 43 and 44 in their respective rows of notches cut in the plate 42, suitable flat bars 55 are secured to opposed sides of the plate.

50 There are times when it is necessary to raise the rows of splits 43 and 44, such as when a lease thread is being drawn through the shed of a moving warp. The function of these rows of splits is to prevent the inserted lease thread from moving longitudinally along with the warp. When it is desired to raise the combs or splits 43 and 44 from the position shown in Figure 2 to the position shown in Figure 3, a suitable handle 56 is employed, said handle being pivoted as at 57 to the upright 41. The innermost end of the handle 56 has a slot 58 therein for accommodating a bolt 59 in the lower end of a vertically disposed rod 60. This rod has its intermediate portion slidably mounted in flange 61 of the hollow shaft member 47 and the upper end of this rod engages a suitable sponge rubber washer 62. Member 62 is disposed around the shaft 46 and directly over the flange 61, and serves to prevent noise and vibration as a result of sudden lowering of the combs or splits 43 and 44.

55 When the splits 43 and 44 have been raised to the position shown in Figure 3, a suitable locking mechanism automatically comes into action to latch the splits in this position. This locking mechanism comprises levers 65 and 66 pivoted as at 67 and 68, respectively, to the bars 48. The lower end of the lever 65 has a projection 65a which extends horizontally through a

slot 70 in the hollow shaft member 47. After the lower end of the shaft 46 has been moved upwardly sufficiently to clear the projection 65a, this projection is rotated beneath the shaft 46 to thereby serve as a latch. Simultaneously, with the movement of the projection beneath the shaft 46 (Figure 3), the other end of the arm 65 moves downwardly against projection 66a and is engaged by hook member 66, which serves to hold the lever 65 in position until it is released by means which will be hereinafter described. As the horizontal leg of lever 65 moves downwardly, the end thereof engages projection 66a on lever 66 to cause a slight clockwise rotation of the hook on the upper end thereof, thereby causing the hook to be in the path of the horizontal leg when it again moves upwardly.

Suitable means are also provided for clamping the ends of the lease string at opposed edges of the warp. This clamping means is actuated simultaneously with the raising of the splits 43 and 44 which serve as combs for preventing longitudinal movement of the inserted lease string along with the warp. One of the clamping means comprises a plate 75 which is secured by any suitable means such as screws 76 to one end of plate 42. Figure 7 illustrates this structure in detail. It is here seen that the plate 75 has a groove 78 on the under side thereof which accommodates the intermediate portion of the lease string 32.

When it is desired to take a lease, a string of suitable length is doubled upon itself, and the central portion of this string is placed in the groove 78 thereby allowing the ends to fall downwardly toward the floor. When the splits or combs 43 and 44 are raised from the position shown in Figure 2, to the position shown in Figure 3 a suitable clamping member 80 is caused to move upwardly into the groove 78 and clamp the intermediate portion of the lease string 32 in position. This clamping member is mounted on the upper end of a rod or shaft 81, which shaft reciprocates up and down in bore 82 disposed in the plate 42. The intermediate portion of the rod 81 has a slot 84 therein (Figure 3) which is penetrated by a projection 85 extending laterally of the warp from the end of the member 45, said member 45 being the member which supports the combs or splits 43 and 44. In order to permit a substantial vertical movement of the projection 85, a vertically disposed slot 87 is cut in the sidewall of support 40. Also springs 88 and 89 are disposed above and below the projection 85, respectively. The slots 84 and 87 and spring 88 permit a relatively small amount of vertical movement of members 80 and 81. Figure 3 shows spring 88 compressed, at which time, the upper end of the clamping member 80 is engaging the least string 32.

The clamping means on the other end of the lease forming apparatus is very similar to the clamping means just described (Figures 3 and 8). Likewise the member 45 has a projection 91 extending therefrom laterally of the warp through a slot 92 in the upper end of hollow support 41. Within the support 41 the projection 91 penetrates a slot 93 in a downwardly extending rod 94. This rod has its upper intermediate portion slidably mounted in a bore 95 cut in the lower surface of the plate 42 and the extreme upper end of the rod 94 has a plate 98 integral therewith upon which the inserted ends of the lease string 32 are adapted to rest. Disposed above and below, respectively, the projection 91 are

springs 99 and 100, which serve as a cushion to allow the plate 98 on the upper end of the rod 94 to resiliently engage the ends of lease string 32 and press them upwardly against overhanging stop 101. Stop 101 is secured to a lug 102 by any suitable means such as screws 103, said lug being an integral part of the plate 42 (see Figure 8). It is therefore seen that each time the combs 43 and 44 are raised to the position shown in Figure 10 3 that the clamping members 80 and 98 will simultaneously be moved upwardly in contact with groove 78 and overhanging member 101 respectively. On very narrow warps the combs 43 and 44 may be dispensed with and the selvage clamps employed to hold the inserted lease string, or if desired the combs may be used without the clamps.

It will be noted by referring to Figures 2 and 7 that the plate 75 has an upstanding pin 105. 20 This pin serves as a guide for the end of lease bar 107 which is shown in Figures 10 and 11. One end of the lease bar has a hole 108 therein and a slot 109 which leads from this hole to the edge of the bar. This slot permits the lease thread to be inserted therethrough and into the hole 108. The other end of the bar 107 has a handle portion 110 which the operator uses when a lease is being taken.

The operation of the invention is as follows: 30 a lease thread 32 of suitable length is doubled upon itself and the intermediate portion thereof inserted in the groove 78, shown in Figures 2 and 7. Then the handle 26 (Figure 1) is rotated downwardly until the reed 19 is raised to dotted line position 18a. At this time, the warp ends W1 will be in a substantially horizontal plane, whereas the alternate warp ends W2, will be in raised dotted line position thereby forming a shed. At this time, the member 107 as shown in 40 Figure 10 will be inserted between the layers W1 and W2 and then moved longitudinally of the warp until it rests upon plate 42 in the position shown in Figure 11. Now, the portion nearest the observer of the member 107 is resting beneath the overhanging portion 101 and on top of the clamping plate member 98; whereas the portion remote from the observer is resting directly on top of the plate 75. One end of the lease string 32 is then placed in the hole or hooked portion 108 of the member 107 after which the lever 56 in Figures 2 and 3 is pressed so that the combs or splits 43 and 44 will be raised from the position shown in Figure 2 to the position shown in Figures 3 and 12. At this time, the bar 107 is pulled towards the observer in Figure 11 to thereby draw one end of the clamped lease string 32 through the shed above the warp ends W1 and below the warp ends W2, and also to be drawn beneath the overhanging member 101 and above the clamp member 98.

It should be borne in mind that immediately upon the raising of the combs 43 and 44, that the clamping members 80 and 98 will simultaneously be raised to clamp the lease string 32 and the bar 107. However, this clamping action will not be sufficient to prevent the bar 107 from being moved toward the observer in Figure 11 to draw the end of the lease string 32 between the warp ends W1 and W2 and between the members 101 and 98.

The next step is to rotate the lever 26 in Figure 1 in a clockwise manner until the reed 19 moves downwardly to dotted line position 18b, at which time the warp W1 is substantially horizontal and the warp W2 is in lowermost dotted line position.

Then the bar 107 is inserted between the sheds W1 and W2 and moved longitudinally of the warp until it rests against the comb 44. The other end of the lease string 32 is now inserted in the hook portion 108 and drawn between the newly formed sheds W1 and W2 and between the members 98 and 101. With the lease string properly drawn through the respective sheds a knot 115 is tied thus causing the lease string to be an endless band which is loosely woven into the warp.

After tying the lease string, the combs 43 and 44 are allowed to remain in raised position to prevent the lease string from moving along with the warp. Also the clamping members 80 and 98 are in clamping position to clamp the ends of the inserted lease string.

When a predetermined number of yards of warp have been run past the leasing machine, means are automatically actuated to allow the clamping members 98 and 80 to release the ends of the lease string and allow it to move along the warp. This means comprises a magnet 116 (Figure 13) which has a wire 117 leading therefrom, and the other end of the wire is adapted to be contacted by switch bar 118. The other side of the switch bar is adapted to make contact, at times, with wire 119, said wire leading to battery 120. Wire 121 leads from the other side of the battery 120 and is adapted to have its other end contacted at times by another switch bar 122, said switch bars 118 and 122 being joined to a common bar 123 which is actuated by a cam 124 on counting mechanism 125. When a predetermined number of yards have been run, the counting mechanism rotates the high side of cam 124 against the bar 123 thereby causing the bars 118 and 122 to close the circuit between wires 117, 119, 121 and 126. The current is then allowed to flow through the magnet 116, which, in turn, will cause the latch 66 to rotate in a counter-clockwise manner and release the end of lever 65, which in turn will release the shaft 46 and the combs 43 and 44 to allow them to move downwardly under the force of spring 50.

Leading from the other side of the magnet 116 is a wire 127, said wire leading to terminal 128. Likewise wire 126 leads to a terminal 129 and both of these terminals are normally contacted by a bar 130 of switch 132 which bar is normally urged into contacting relation by compression spring 131.

When the combs 43 and 44 are in raised position, the contacts 128 and 129 are engaged by the bar 130, but immediately upon falling, this contact is broken. The purpose of the switch 132 is to insure that the current will be broken immediately after the solenoid 116 has been energized to allow the combs to fall. Sometimes, the machine, for one reason or another, is stopped within a yard or so after the lease string has been released by the combs and clamps. Since the current remains on the magnet 116, for a yard or two after the lease string has been released, it is seen that if the machine is stopped within this length of warp that the magnet will continue to be energized and therefore would suffer damage as a result of being subjected to current for too long a period.

Figures 14 to 18 inclusive show a slightly modified form of the lease forming apparatus having an improved means for inserting the lease threads in the sheds of the moving warp. In the previous form of the invention the bar 107 was employed for drawing the ends of the lease

thread through the sheds. Due to the fact that this bar has to be manually lifted and inserted through the warp, very often the warp ends become entangled with the bar. The present modification provides positive means for directing the thread through the warp sheds so as to insure that entanglement with the warp ends will not occur.

In order to provide this positive means for guiding the lease threads through the sheds, a suitable pipe 140 has been mounted in brackets 141 and 142, on one side of the apparatus 24. This pipe has a rod 143 slidably mounted therein, said rod having a pin 144 extending therefrom which penetrates a slot 145 in pipe 140. The right hand end of the rod 143 has a handle 146 secured thereon which is used for sliding the rod to and fro when it is necessary to insert the end of lease threads 32. The left hand end of this same rod extends upwardly and then again horizontally in parallel relationship to the lower portion thereof. The end of the rod 143 is flattened as at 148 (see Figure 18), so that this portion can easily penetrate between the members 98 and 101 which serve to clamp the ends of the lease threads. Portion 148 is forked as at 149 to allow the end of the lease thread 32 to be inserted therein. After inserting the lease thread in fork 149 in the manner shown in Figures 14, 15 and 18, it is only necessary to draw the handle 146 towards the right thereby causing the end of the lease thread to be threaded between the warp sheds W1 and W2 and adjacent the comb 43. When the end has been threaded as shown in Figure 18, the operator grasps the end of the lease thread 32 and at the same time, the handle 146 is used to push the rod reversely out of the shed to the position shown in Figure 15, leaving the end of the lease thread clamped between members 98 and 101.

Another apparatus for inserting the other end of the lease thread is shown in Figure 16, which is used on the opposite side of the machine from the location the apparatus just described. This comprises a slotted pipe 155, having a slot 156 therein, which slot is penetrated by a projection 157 on U-shaped rod 158. Pipe 156 is mounted in brackets 159 and 160 which, in turn, are secured to the member 24. The upper end of the U-shaped rod 158 has a flattened portion 148 identical to the flattened portion 148 previously described on rod 143 and a forked end portion 149 is provided which is identical to the forked portion on the previously described lease inserting means. A handle 162 is secured on the left-hand end of the rod 157 in Figure 16 and this handle is employed for drawing the U-shaped rod to the left after the end of the lease thread 32 has been threaded into the forked end. The operation of rods 143 and 158 are identical except they are used in connection with different warp sheds.

In the drawings and specification there has been set forth a preferred embodiment of the invention, and although specific terms are employed, they are used in a generic and descriptive sense only and not for purposes of limitation, the scope of the invention being set forth in the appended claims.

I claim:

1. In apparatus for placing lease threads in a moving warp, a plate disposed transversely of the warp, a pair of vertically movable combs disposed below the plate and having their splits slidably penetrating holes in the plate and nor-

mally projecting a substantial distance above the plate and forming dents through which the warp threads pass, a vertically movable shed forming device through which the warp threads pass, means for inserting a lease thread through a shed in advance of each comb, a clamp disposed on each end of the plate for clamping the lease threads, means for simultaneously lowering the combs so that their upper ends will be disposed below the upper surface of the plate and for opening said clamps to allow the lease thread to be carried along by the moving warp.

2. Means for placing lease threads in a moving warp comprising means for forming a pair of spaced sheds in the warp while it is moving, means for inserting the two ends of a lease thread through the sheds, clamping means adjacent each edge of the warp for securing the lease threads against movement on account of contact with the moving warp, a pair of spaced combs penetrating the moving warp for preventing the lease threads from being carried along by the moving warp, there being a comb for each lease thread, means for simultaneously releasing the clamping means and withdrawing said combs at predetermined intervals to allow the lease threads to be carried along by the moving warp.

3. Mechanism for taking a lease in a moving warp comprising a plurality of transversely disposed parallel spaced combs adapted to penetrate the warp, means for forming a plurality of warp sheds one at a time, means for inserting a lease thread in each of said sheds alongside each of said combs, a clamp at each end of the combs for clamping the lease threads, and means for simultaneously withdrawing said combs from the warp and opening said clamps to allow the lease thread to be carried along with said warp.

4. Apparatus for forming a lease in a moving warp, comprising means at one edge of the work for clamping a thread intermediate its ends along one edge of the warp, means for successively forming sheds in the warp, a pair of spaced transversely disposed combs through which the warp passes, means for inserting each end of the thread in a shed in front of the combs, means at the other edge of the warp for clamping the inserted ends of the lease thread in stationary position, and means for simultaneously releasing both of said clamping means and for lowering said combs out of contact with the work to allow the thread to be carried along with the warp.

JAMES W. SHERRILL.
